TRIM FOR DOOR HARDWARE

Richard J. Ohno, Branford, Conn., assignor to Sargent & Company, New Haven, Conn., a corporation of Connecticut

Application March 31, 1955, Serial No. 35,304

Term of patent 14 years

(Cl. D10—8)

Fig. 1.

Fig. 2.

Fig. 1 is a front elevational view of a trim for door hardware embodying my new design; and

Fig. 2 is a side elevational view thereof.

The essential features of the design reside in the solid line portions.

I claim:

The ornamental design for a trim for door hardware, as shown and described.
